UNITED STATES PATENT OFFICE.

MAURICE B. SHWAYDER, OF DENVER, COLORADO, ASSIGNOR TO SHWAYDER TRUNK MANUFACTURING CO., OF DENVER, COLORADO, A CORPORATION OF COLORADO.

HANDLE FOR TRAVELING BAGS, SUITCASES, ETC.

Application filed September 27, 1926. Serial No. 137,946.

This invention relates to a handle to be used on suitcases, traveling bags and the like, and has for its principal object the provision of a handle construction which 5 can be cheaply manufactured, will eliminate all the sewing and padding necessary on present handles, which will be strong and serviceable, and which will simulate in appearance the present style of sewn and padded handles.

Another object is to provide a handle which will not be affected by moisture, oils, perspiration, etc., and which will not rip or become misshapen from use.

Other objects and advantages reside in the detail construction of the invention, which is designed for economy, simplicity, and efficiency. These will become more apparent from the following description.

In the following detailed description of the invention reference is had to the accompanying drawing which forms a part hereof. Like numerals refer to like parts in all views of the drawing and throughout the 25 description.

In the drawing:

Fig. 1 is a perspective view of a suitcase with my improved handle in place thereon.

Fig. 2 is a perspective view of the handle 20 as used in Fig. 1.

Fig. 3 is a cross section through the same, taken on the line 3—3, Fig. 2.

Fig. 4 is a longitudinal section, taken on the longitudinal center line of the handle 35 of Fig. 2.

Fig. 5 is a perspective view of an alternate style of handle, known as the round type.

Fig. 6 is a cross section through the type 40 of Fig. 5, taken on the line 6—6, Fig. 5.

In Fig. 1 a suitcase is illustrated at 10 provided with the usual handle straps 11 to which the links 12 for a handle 13 are secured. The handle 13 is illustrated in detail in Figs. 2, 3 and 4 and comprises a metallic tie strip 14 the ends of which are formed in loops 15 after which they are

turned backward upon the strip 14, as at 23. The links 12 are passed through the loops 15 of the tie strip.

The combined tie strip and links are then placed in a mold and cast into a solid block of relatively soft rubber 16 which surrounds and conceals the tie strip and its loops 15. The rubber block 16 is preferably formed 55 to simulate a built up leather handle, it having projections 17 formed thereon to simulate the seams of a built up handle.

In Figs. 5 and 6 the invention is illustrated as applied to the usual round type of handle. In this form a tie strip 18 is employed, terminating in loops 19. The strip 18 and its loops 19 are embedded in a cast rubber covering 20, there being openings 21 molded in the covering to align with the 60 openings in the loops 19 for the reception of attachment links. The covering 20 is provided with suitable longitudinal indentations 22 to simulate the seams usually found in a round padded leather handle.

The rubber can be made in differing colors to match the color of the suitcase or bag upon which the handle is to be used. Rubber is, of course, impervious to moisture and makes a much more durable handle than 75 the present padded, sewn leather handle.

While a specific form of the improvement has been described and illustrated herein, it is desired to be understood that the same may be varied, within the scope of the appended claim, without departing from the spirit of the invention.

Having thus described the invention, what I claim and desire to secure by Letters Patent is:

A handle for suitcases and the like comprising a metallic tie strip terminating in loops; a unitary rubber casing molded around said strip; and links molded within said casing so as to pass through said loops 80 for attaching said handle to said suitcase.

In testimony whereof, I affix my signature.

MAURICE B. SHWAYDER.
